(57) **CLAIM**

The ornamental design for a portable ramp with pad and stabilizers, as shown and described.

DESCRIPTION

FIG. 1 is a top plan view of the portable ramp with pad and stabilizers showing the first embodiment of my design; FIG. 2 is a right elevation view, the left being a mirror image thereof;

FIG. 3 is a right elevation view of a second embodiment, the left being a mirror image thereof;

FIG. 4 is a front elevation view thereof; and,

FIG. 5 is a rear elevation view thereof.
